DESIGN FOR A SNOW SUIT

David Itkin, New York, N. Y.

Application May 13, 1935, Serial No. 56,822

Term of patent 7 years

To all whom it may concern:

Be it known that I, David Itkin, a citizen of the United States, residing in the county of Kings, city and State of New York, have invented a new, original, and ornamental Design for a Snow Suit, of which the following is a specification, reference being had to the accompanying drawing, forming part thereof.

Fig. I is a front view and Fig. II a rear view of a snow suit showing my new design.

The characteristic feature of the design resides in the use of materials of contrasting texture, represented by the shaded portions in the drawing, to prick out the pattern shown.

I claim:

The ornamental design for a snow suit as shown and described.

DAVID ITKIN.
